UNITED STATES PATENT OFFICE

2,284,932

ELECTRICALLY OPERATED PUMP JACK

William B. Thiemann, Albert City, Iowa

Application January 15, 1940, Serial No. 313,907

3 Claims. (Cl. 74—44)

The object of my invention is to provide a simple durable and inexpensive pump jack particularly adapted to be operated by means of a small electric motor.

A further object of my invention is to provide an improved pump jack which is silent in its operation and provided with means for balancing the weight of the pump rod, wherein a more uniform load will be applied to the electric motor.

A further object is to provide an improved pump jack, including a pair of crank elements and lift bars connected therewith in such a manner that the lift bars are operated on opposite sides of the pump by cranks driven by belts from a single jack shaft, and in connection therewith an independent belt tightener for each of said belts wherein a maximum amount of power may be transmitted through the belts with a minimum amount of slippage.

A further object is to provide in a pump jack employing a pair of upright lift bars connected to the upper end of a pump rod and employing a crank mechanism set to one side of the pump stock, an improved anti-friction device for carrying the pressure side of the pump rod as the lift bars are operated to lift said rod.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a side elevation of my improved pump jack showing the manner in which it is applied to a pump;

Figure 2 is an end elevation of same;

Figure 3 is a top plan view of my improved pump jack, a portion of which is shown in section on the line 3—3 of Figure 1;

Figure 4 is an enlarged detail sectional view taken on the line 4—4 of Figure 1;

Figure 5 is an enlarged detail sectional view taken on the line 5—5 of Figure 2.

On the drawing I have used the reference numeral 10 to indicate a pump stock and 11 a guide supporting bracket for slidably supporting the upper end of the pump rod 12, said pump rod being of the ordinary construction.

My improved pump jack comprises a supporting bar 13 having at one end a vertically arranged leg 14 and at the other end a clamp device 15, said clamp device 15 being designed to secure one end of the frame member 13 to the pump stock 10 in a detachable manner. Fixed to the inner end of the member 13 is a pair of

bearings 16 in which is rotatably mounted a crank shaft 17. Each end of the shaft 17 is provided with a belt wheel 18, each of said wheels including spokes 19, one of said spokes being provided with a wrist-pin 20. Pivotally connected to each of the pins 20 is an upright lift bar 21 mounted outside of the wheels 18, and on opposite sides of the pump stock 10 and the bracket 11, as clearly illustrated in Figure 2.

Connected to the upper ends of the bars 21 is a cross bar 22 having at one side a laterally projecting bracket 23 which provides means for connecting the end of the lift bars 21 to the pump rod 12 by means of a pin 24. By this arrangement it will be seen that if the wheels 18 are rotated, then the bars 21 will be elevated and lowered, causing the pump rod 12 to be elevated and lowered.

For counter-balancing the weight of the pump rod 12 I have provided on the upper ends of the guide bracket a cross bar 25 which is detachably secured thereto by means of bolts 37 projecting through a bar 27 supported on the opposite side of the bracket 11 in the manner clearly illustrated in Figure 4. Each end of the bar 26 is provided with a hook 28 for supporting the upper ends of springs 29, the lower ends of the said springs 29 being secured to pins 30 carried by the lift bars 21, said springs thus providing means for balancing the weight of the rod 12, the tension of the said springs 29 being adjusted by simply elevating and lowering the bars 25 and 27 relative to the guide bracket 11.

Adjustably fixed to the outer face of the bar 27 is a pair of bracket members 31 by means of the bolts 26 in slots 27a, said brackets 31 being mounted on opposite sides of the pump rod 12 and having supported between their outer ends a roller 32 by means of a bolt 33, said roller 32 being designed to engage the outer edge of the bar 12 and serve as an anti-friction device at the time power is applied to the rod 12 to lift the same. This roller 32 provides means for relieving the guide 34 of undue wear, the said guide 34 being a part of the ordinary pump construction.

For rotating the wheels 18 I have provided on the outer end of the bar 13 bearings 35 in which is rotatably mounted a jack shaft 36. Each end 50 of the shaft 36 is provided with a belt pulley 37 in alignment with corresponding belt wheels 18, the pulley 37 being adapted to receive V belts 38 which are adapted to operate over the flat belt wheels 18. A belt tightener pulley 39 is provided for each of the belts 38, said pulleys 39

being mounted on a pivoted lever 40 carried by a post 41. A spring 42 provides means for yieldably applying pressure to the idler pulley 39 and to the belts 38. Thus means is provided for independently supplying tension to each of the belts 38. A belt wheel 42 is also fixed to the shaft 36 and is driven by a belt 43 and by an electric motor 44, said motor 44 being mounted on the upper end of a pedestal 45 carried by the upper edge of the frame member 13.

By this arrangement it will be seen that the belt 43 may be driven by means of the motor 44, which in turn will cause the wheel 42 to rotate, and with it both of the bars 37, both belts 38 and both of the wheels 18, and with them the shaft 17 which is fixed to both of said wheels 18. Rotation of the wheels 18 will cause both of the lift bars 21 to be elevated in unison, and in turn the bar 22, causing the rod 12 to also be elevated as the wheels 18 are rotated through an angular path of 180°. Tension will be applied to the springs as the lift bars are moved downwardly through further 180° of rotation of said wheels, thus providing means whereby a more uniform and even load will be applied to the belts 38 and in turn to the motor 44 which usually employs a very small light armature, thus providing means whereby the motor will rotate more uniformly, and inasmuch as all of the speed rotation is through belts, the noise is eliminated to a minimum, the belt tightener 39 providing means for taking up slack in the belts each time that excessive loads are applied to said belts.

Thus it will be seen I have provided a pump jack of very simple construction wherein the shaft 17 is located near the stock 10 so that a very small amount of angular strain is applied to the pump rod on the lifting stroke, the pulley 32 serving as an anti-friction device to carry this small amount of angular strain as applied to said rod. By providing two lift rods 21 on opposite sides of the pump, lateral strain applied to the sides of the lift rod 12 will be eliminated. The pulley 32 is adjustably mounted in the brackets 31 by means of slots 45 in which the bolt 33 is mounted, so that the said pulley 32 may always be held in contact with the edge of the said rod 12.

I claim as my invention:

1. In combination, a pump stalk having at its upper end a pair of upwardly extending guide supporting brackets, a horizontal supporting bar, a clamp at one end of said bar for detachably securing said bar to said pump stalk, a leg supporting the other end of said supporting bar, a

transverse shaft at each end of said bar, flexible means for operatively connecting said shaft, an upright pedestal carried by said supporting bar intermediate its ends, a motor platform carried by said pedestal, flexible means transmitting power from said motor to one of said shafts, a pair of lift bars, means for operatively connecting said lift bar to the other one of said shafts to impart reciprocating motion thereto, an upright post on each side of said leg, means carried by the upper end of each of said posts for tightening the first said flexible means, means for operatively connecting said lift bars to the upper end of the pump rod carried by said stalk to operate the horizontal clamping bars, means adjustably clamping said bars to said brackets, a pair of laterally projecting and spaced bracket members adjustably secured to one of said clamping bars to move toward and from each other, a roller between the outer ends of said bracket members, and means adjustably mounting said roller in said shaft members to move toward and from said bars substantially as described, for the purpose stated.

2. In a device of the class described, the combination of a pair of upright supports having a pump guide at their upper ends, horizontal clamping bars, means adjustably clamping said bars to said supports to slide longitudinally thereof, a pair of laterally projecting and spaced brackets adjustably secured to one of said clamping bars to move toward and from each other, a roller between the outer ends of said brackets, and means adjustably mounting said roller in said brackets to move toward and from said bars substantially as described and for the purpose stated.

3. In a pump jacket having at its upper end a pump rod guide carried by upright supports, a pump rod slidably mounted in said guides operated by mechanically actuated lift bars, said lift bars being operated in a line of movement at an angle relative to the line of movement of said pump rod, an anti-friction device for carrying the lateral pressure imparted to the rod by said angular movement, comprising a clamping bar, means adjustably securing said bar to said guide supports to move longitudinally thereof, a bracket on each side of said rod adjustably secured to said clamping bar to move toward and from each other, a roller between the outer ends of said brackets adapted to engage the pressure side of said rod, and means adjustably and pivotally mounting said roller in said brackets.

WILLIAM B. THIEMANN.
